LINK TOY

Joseph J. Schigas, Erie, Pa., assignor to Louis Marx & Company, Inc., New York, N. Y., a corporation of New York

Application August 14, 1952, Serial No. 304,259

5 Claims. (Cl. 46—16)

This invention relates to toys, and more particularly to a toy for doodling or fiddling with in idle moments.

The general type of toy is already known, it comprising a series of pivoted bars somewhat resembling a fence, and preferably making up a closed ring. There are a sufficient number of pivoted units, say twelve, to make it possible to re-arrange the units into a variety of formations, and considerable entertainment is derived in seeing how many varied formations may be obtained, and in searching for additional new formations.

As heretofore made the toy has comprised a large number of individual bars, drilled and pivoted together at their ends by wire links. Thus alternate sections of the fence might comprise four such bars, and the intermediate sections three such bars, the bars being interleaved at their ends so that the three bars serve to space apart the four bars, and vice versa. The cost of manufacture and assembly was high, and the resulting product was not as durable as would be desired, considering that it is subjected to hours of manipulation, and sometimes abuse. Moreover, there is a tendency for the pivot action between sections to become loose, in which case some irritation arises because of difficulty in holding desired formations as they are being made up.

The primary object of the present invention is to generally improve toys of the specified character, and to overcome the foregoing difficulties, while providing a toy of improved appearance and economical manufacture.

In accordance with one feature and object of my invention the toy is made up of links or sections each having a plurality of spaced parallel bars, and these bars are joined in fixed spaced relation by connections therebetween, the said connections preferably being disposed midway of the ends, and the entire link, including all of the bars and connections, being molded in its entirety as a single integral unit.

In a particular preferred form of the invention each link may be provided with an even number of bars at one end, and one less number of bars at the other end, the said bars overlapping at the middle of the link to form the aforesaid connections between the bars of the single integral link. Moreover, these connections or overlapping portions are preferably cut away or tapered to facilitate close folding together of the links.

In accordance with a further object of the invention the successive links are pivotally joined by mating pins and sockets, both of which are molded integrally as a part of the links. The sockets are open and designed to receive the pins with a snap fit, this fit preferably being frictional so that the links tend to hold any formation into which they are put. Moreover, the sockets at one end of a link are preferably formed by cutting away the ends of the successive super-imposed bars of that link at angles in opposite direction. The end of each bar is widely open, but the combined ends of three or more bars are sufficiently closed to hold the aligned mating pins. Thus the snap engagement of the socket is afforded by the bending resilience of the bars over the

2

full distance between the mid connections and the sockets.

In accordance with still another feature and object of the invention the pins are formed at a link end having an even number of bars. In this way each pin is supported at both ends, and acts as an additional spacing means between bars. As a corollary, the open-ended sockets are formed at that end of a link having an odd number of bars. The odd number is always made one less than the even number, and the cut away ends are therefore concealed from view when looking at the formations into which the toy may be put.

A still further object of the invention is to so design the links that they may be folded or nested closely against one another. Still another object of the invention is to so relate the arms of the links as to establish and maintain a frictional relationship at the pivots, this friction being permanently retained by reason of the bending resilience of the arms of the pivots, and involving a bending both in the plane, and transversely of the plane, of the arms.

To accomplish the foregoing objects, and other objects which will hereinafter appear, my invention resides in the toy elements, and their relation one to another as are hereinafter more particularly described in the following specification. The specification is accompanied by a drawing, in which:

Fig. 1 is a diagrammatic view showing one typical formation into which the toy may be put;

Fig. 2 is a similar view showing another formation;

Fig. 3 is a front elevation of a preferred form of link;

Fig. 4 is a bottom plan view of the link shown in Fig. 3, before being joined to another link;

Fig. 5 is a horizontal section taken approximately in the plane of the line 5—5 of Fig. 3, showing the link before being joined to another link;

Fig. 6 is a view similar to Fig. 4, after the link has been joined to adjacent links, and showing how the links may be folded or nested together;

Fig. 7 is a transverse section taken approximately in the plane of the line 7—7 of Fig. 3;

Fig. 8 is a front elevation of a female link for a modified form of my toy;

Fig. 9 is a plan view thereof;

Fig. 10 is a front elevation of a male link for the modified form of my toy; and

Fig. 11 is a fragmentary plan view of the link shown in Fig. 10.

Referring to the drawing, and more particularly to Fig. 1, the complete toy here illustrated comprises twelve sections or links L. These are pivoted end to end in such fashion that they may be folded relative to one another in either direction. Thus the sections may be arranged to form a square with four points, as shown in Fig. 1; or a three-pointed star, as shown in Fig. 2, or any of numerous far more intricate formations. Each link comprises a series of simulated bars superposed in a common plane, and a preferred form of a single link is shown in Figs. 3 through 7 of the drawing.

Referring to Fig. 3, the link L has a plurality of bars 12, 14, 16, 18, 20, 22 and 24, all lying in substantially the same plane and joined in fixed spaced relation by connections 26 therebetween. These bars receive the bars of adjacent links in interleaved relation, and the four bar end of an adjacent link is shown in dotted lines at the left of Fig. 3, while the three bar end of an adjacent link is shown in dotted lines at the right of Fig. 3. Each link is molded in its entirety out of a suitable molding plastic as a single integral unit, that is, the bars 12 through 24 are all made as a single molded piece with fixed connection therebetween intermediate the ends.

In the present form of the invention the connections are coincident with an overlap of the bars. The over-

lapping or connecting portions are preferably cut away or tapered, as is clearly shown at 28 and 30 in Fig. 4 of the drawing. In effect the connecting portions at the center are somewhat diamond-shaped, as shown in Fig. 5, but there is no actual section like that shown in Fig. 5, the result shown in Fig. 5 being obtained by stepping the section upward, as shown by the change in elevation of the line 5—5 in Fig. 3. This cutting away of the overlapping portions permits the links to fold as closely together as though there were no overlapping portions, for the three bar portions fit between the four bar portions of the adjacent links, and vice versa.

The link L has pins 32, and mating sockets 34 and 36. These pins and sockets are molded integrally as a part of the links. Moreover, the sockets are open and so designed as to receive the pins of an adjacent link with a snap fit, thus minimizing the time and labor needed for assembly of the toy. More specifically, and referring to Fig. 4, the socket 34 at the end of the arm 16 is cut away and quite open, the end 38 being at an angle of about forty-five degrees, while the part 40 may extend transversely of the link in order to facilitate the molding operation. Referring now to Fig. 5, the socket 36 is cut away in opposite direction, the part 42 being at an angle of about forty-five degrees, but of opposite slope to the part 38 in Fig. 4. There is a transverse surface at 44.

It will be understood that by thus making the ends of the successive bars open at angles in opposite directions the combined ends of three or more bars are sufficiently closed to hold the superposed pins of an adjacent link. To assemble the links it is merely necessary to push them together, and the resulting snap engagement is afforded by the bending resilience of the bars 12, 14 and 16, the bars 12 and 16 bending in one direction, while the bar 14 bends in opposite direction.

Moreover, to insure longer maintained frictional fit the links may be initially molded with a slight angular displacement of the bars. Specifically, while all of the bars lie essentially in the same plane, it will be seen from examination of Fig. 4 that the bar 16 is initially molded at a slight angle relative to the plane of the bars 18—24. This angle is indicated at A in Fig. 4, and in a specific case was 2½ degrees. The bar 14 is molded at a slight opposite angle, indicated at B in Fig. 5, with respect to the plane of the link. Here again the angle may be quite small, say 2½ degrees, and is eliminated when the links are snapped together, for the arms 12, 14 and 16 are brought into substantial alignment by the three superposed and properly aligned pins of the mating adjacent link. This bias or pre-loading of the bars insures a secure engagement and holding grip of the sockets on the pins, and a maintained friction at the pivots.

As will be seen from inspection of Fig. 3, the pins 32 are preferably provided at the end of the link having an even number of bars, so that each pin is supported at both ends. In this way the pins act also as additional spacer means to maintain the spacing and parallelism of the bars 18—24. The sockets are formed at that end of the link having an odd number of bars, which number is one less than the even number. An incidental result of this is that the cutaway or socket ends are concealed between ends which are not cut away.

In accordance with a further feature of the invention the bars are additionally biased or pre-loaded in another direction to maintain the desired frictional pivoting action between links. Specifically, the distance C shown in Fig. 3 is made greater when molded than the distance D, so that the top and bottom bars 12 and 16 are bent toward one another slightly when the links are assembled. This difference in dimension is quite small, and in one specific case where the dimension D was 0.930", the dimension C was 0.950".

It is not essential to form each link with half-length bars, and with a different number of bars at each end. A variant form of the invention is illustrated in Figs. 8

through 11 of the drawing. In this case the toy is made up of alternate male links, and intermediate female links. A male link is shown in Figs. 10 and 11, and it comprises four superposed parallel bars 50 held apart in spaced relation by connections 52 therebetween, and additionally properly spaced by end pins 54. It will be understood that the bars 50, the connections 52, and the pins 54 are all molded integrally in a single molding operation.

A typical female link is shown in Figs. 8 and 9. This comprises three superposed parallel bars 56, 58 and 60, held in fixed spaced relation by connections 62 therebetween. Sockets are formed at the ends of the bars, and these may be substantially the same as previously described, that is, successive bars may be cut away at oppositely directed angle. Thus in Fig. 9 the end of the bar 56 is cut away at angle 66, and the end of the bar 58 is cut away at the angle 64. In this way three or more bars will form a closed socket. Similar open sockets are combined to form a closed socket formed at the other end of the link.

It will be understood that male and female links are snapped together in alternation, there being six of each in the specific toy here shown, but a greater or lesser total number could be provided. It will also be understood that refinements such as bias or pre-loading of the arms 56, 58 and 60 in opposite directions, as indicated by the angles A and B in Figs. 4 and 5, and in the plane of the link, as indicated by the dimensions C and D in Fig. 3, may also be used in connection with the female link shown in Fig. 8. It will further be understood that while the connections 62 between the bars of the female link shown in Fig. 8 are essential for integral molding of an entire link at a time, the connections 52 in the male link of Fig. 10 are not similarly indispensable, because the pins 54 themselves act as spacers. However, it is preferred to use connections 52 in the male link because of the additional strength of the finished part, and the greater ease of molding because of the freer flow of material between the parts of the mold cavity.

Finally it will be understood that additional refinements such as a generally diamond-shaped cross-section for the connections 52 and 62 may be provided, much as shown at 28, 30 in Fig. 5 of the drawing, thus permitting the bars of the successive links to interleave or nest closely together when links are folded against one another, as is desirable when producing certain formations. A slight beveling for this purpose is shown in broken lines in Fig. 9 at 62, but the bevel may be carried further, as shown in Figs. 4 and 5.

It will be understood that the form of the invention shown in Fig. 3 may be made without the pre-load angle indicated at A and B, and the pre-load bias indicated at C and D, these being desirable but not essential refinements.

It is believed that the construction, method of assembly, and method of use of my improved toy, as well as the advantages thereof, will be apparent from the foregoing detailed description. It will also be apparent that while I have shown and described the invention in several preferred forms, changes may be made in the structures disclosed without departing from the scope of the invention as sought to be defined in the following claims.

I claim:

1. A toy comprising links pivoted end to end, each link having a plurality of relatively long spaced bars lying in substantially the same plane and joined in fixed spaced relation by a transverse connection therebetween, and each link being molded in its entirety as a single integral unit, the spacing between the bars increasing somewhat from the transverse connection toward one end of the link, in order to introduce friction which is maintained in axial direction by the bending resilience of the bars.
2. A toy comprising links pivoted end to end, each link having a plurality of relatively long spaced approxi-

mately parallel bars lying in substantially the same plane and joined in fixed spaced relation by a transverse connection therebetween, and each link being molded in its entirety as a single integral unit, the sockets at one end of a link being formed by cutting away the ends of successive bars at angles in opposite directions so that the snap engagement of the socket is afforded by the bending resilience of the bars between the connections and the sockets, and each bar being initially formed at a slight angle to the plane of the link, the angle of each bar displacing it in that direction in which the socket at the end of the bar is cut away, thereby increasing the radial friction which is maintained at the sockets by the bending resilience of the bars when said bars are brought into the plane of the link by snap engagement with the pins of an adjacent link.

3. A toy comprising links pivoted end to end, each link having a plurality of spaced approximately parallel bars lying in substantially the same plane and joined in fixed spaced relation by connections therebetween, and each link being molded in its entirety as a single integral unit, the sockets at one end of a link being formed by cutting away the ends of successive bars at angles in opposite directions so that the snap engagement of the socket is afforded by the bending resilience of the bars between the connections and the sockets, and each bar being initially formed at a slight angle to the plane of the link, the angle of each bar displacing it in that direction in which the socket at the end of the bar is cut away, thereby increasing the radial friction which is maintained at the sockets by the bending resilience of the bars when said bars are brought into the plane of the link by snap engagement with the pins of an adjacent link, the spacing between the bars in the plane of the link increasing somewhat from the connections toward one end of the link, in order to introduce further friction which is maintained in axial direction by the bending resilience of the bars.

4. A toy as defined in claim 3, in which each link has an even number of bars at one end and one less number of bars at the other end, with the bars overlapping at the middle of the link to form connections between the bars of a single link, and in which the even number of bars

lie in a common plane and integral pins are formed at their ends, while the angularly cut sockets are formed at the end with the odd number of bars, and in which the angle of the bars is an angle relative to the plane of the even number bars.

5. A toy comprising links pivoted end to end, each link having a plurality of spaced approximately parallel bars lying in substantially the same plane and joined in fixed spaced relation by connections therebetween, and each link being molded in its entirety as a single integral unit, the sockets at one end of a link being formed by cutting away the ends of successive bars at angles in opposite directions so that the snap engagement of the socket is afforded by the bending resilience of the bars between the connections and the sockets, and each bar being initially formed at a slight angle to the plane of the link, the angle of each bar displacing it in that direction in which the socket at the end of the bar is cut away, thereby increasing the radial friction which is maintained at the sockets by the bending resilience of the bars when said bars are brought into the plane of the link by snap engagement with the pins of an adjacent link, each link having an even number of bars at one end and one less number of bars not less than three at the other end, with the bars overlapping at the middle of the link to form connections between the bars of a single link, and the even number of bars lie in a common plane and integral pins are formed at their ends, while the angularly cut sockets are formed at the end with the odd number of bars, and the angle of the bars being an angle relative to the plane of the even number bars.
